NEW YORK

STRAP WRENCH

Application filed March 28, 1932. Serial No. 601,518.

This invention relates to pipe wrenches, and more particularly to pipe wrenches of the strap type especially adapted for use in connection with smooth cylindrical surfaces.

Pipe wrenches of the strap type have been found highly desirable because of their ability to be readily adjusted to accommodate many sizes of pipe, and at all times insuring a positive grip. However, the structure of strap wrenches heretofore employed has rendered their adjustment somewhat inconvenient due to the difficulty of sliding the strap through slots in the wrench, the strap having its natural tendency to bind and resist sliding movement. Also, some care and skill is required in properly adjusting the strap to the proper tightness about a pipe to enable rapid and effective manipulation.

It is an object of this invention to provide a strap wrench having a strap which may be readily and conveniently adjusted without the usual annoyance due to binding.

A further object is the provision of a strap wrench which may be quickly adjusted to a pipe without any especial care or skill, and without affecting the gripping action.

A further object is the provision of a strap wrench having a strap having associated therewith nonslippling means to increase the gripping action.

These and other advantageous objects, which will later appear, are accomplished by the simple and practical construction and arrangement of parts hereinafter described and exhibited in the accompanying drawing, forming part hereof, and in which:—

Figure 1 represents a side elevational view of a pipe wrench embodying our invention, applied to a pipe, shown in cross-section,

Figure 2 represents a fragmentary side elevational view of Figure 1,

Figure 3 represents a top plan view of the wrench shown in Figure 1,

Figure 4 represents a perspective view of one end of the strap used in our device,

Figure 5 represents a side elevational

view of the wrench shown in Figure 1, in its double-acting form,

Figure 6 represents a perspective view of a modified form of wrench and showing the manner of applying the wrench to a pipe,

Figure 7 represents a vertical sectional view of the form of invention shown in Figure 6, and

Figure 8 represents a side elevational view thereof.

Referring to the drawing, in Figure 1 is shown the preferred form of our invention, in which a strap wrench includes a block 5, having at one side thereof an inclined slot 6 passing through one side of the block and the rounded gripping surface 7 of the block, said gripping surface 7 projecting beyond each side of the block.

Opposite the rounded gripping surface 7, the block 5 has a pair of short, inclined surfaces 8 and 9, which pass through ears 10 projecting from the block. Pivoted to the ears 10 by means of a pin 11 is a head 12 having a flat surface 13 adapted to cooperate with either of the inclined surfaces 8 or 9 to grip a strap as hereinafter explained. The head 12 is manipulated by means of a handle 14 attached thereto.

A strap 16 passes through the slot 6, and its movement is limited by any suitable or convenient means, as, for instance, by a metal stop 18 which is held in a loop 15 of the strap, (see Fig. 4) the loop being formed by folding the strap back on itself and securing the portions together by a rivet 17.

In operation, the strap 16 is passed around a pipe, and the free end of the strap is passed over the inclined surface 9 and between the ears 10 as shown in Figure 1. The head 12 is moved to cause the flat surface 13 to cooperate with the surface 8 of the block 5 to securely grip the strap, it being obvious that increase in the force exerted in a counterclockwise direction on the handle 14, will increase the gripping action of the head on the strap. It is clear that the structure above described enables ready adjustment of

the strap to fit any size of pipe without in any way impairing the gripping action of the wrench. The strap 16 is preferably made from a strong fabric and has an inner coating 20 of a desirable non-slipping material, such as carborundum, garnet, crepe rubber, or the like.

In some instances, it is desired to make the wrench double acting, that is, able to 10 turn a pipe in either direction without adjustment of the strap, as in the form shown in Figure 5. For this purpose, the block 5 is provided with the inclined slot 19, opposite to and similar to the slot 6. The strap 15 is passed around the pipe as above described, and then through the slot 19, and then over the inclined surface 9 and between the ears 10. The pipe may now be rotated in either direction by causing the flat surface 13 of 20 the head 12 to grip either inclined surface 9 or inclined surface 8.

It is not essential that the surfaces 8 and 9 be inclined, as far as the gripping action is concerned, but by making them inclined 25 there is less cutting action on the strap and this feature is of considerable importance in increasing the life of the strap.

In Figures 6 and 7 is shown a modified form of the invention in which a block 30 has a pair of inclined slots 31 and 32 therein, which pass through the sides of the block and the gripping surface 33 of the block. A strap 36 passes through slot 31 and is detachably fixed therein, preferably by means 35 such as a pin 37 which prevents the strap from being pulled through slot 31. The strap is looped above the surface 33 and the free end of the strap is then passed through inclined slot 32 and thence through a transverse slot 34 in the block. If desired, the 40 free end of the strap 36 may, instead, be first passed through the slot 31, then looped over the surface 33 and the opposite side of the block, and thence through the transverse 45 slot 34 of the block, as shown in dotted lines in Figure 7. A handle 35 is detachably connected to the block. The above structure is double-acting, and enables a pipe to be rotated in either direction without necessitating adjusting the strap. The strap 36 is preferably made of fabric lined with a non-slipping material as above explained.

While the above description discloses the strap wrench adapted for use on pipes and the like, it is obvious that the strap wrench 55 may be made of many sizes and may be readily adapted for use in various situations, and may be used as a kitchen utensil, for removing screw type covers from jars, bottles and the like.

The foregoing disclosure is to be regarded 60 as descriptive and illustrative only, and not as restrictive or limitative of the invention, of which obviously an embodiment may be 65 constructed including many modifications

without departing from the general scope herein indicated and denoted in the appended claims.

Having thus described our invention, what we claim as new and desire to secure by Letters Patent, is:

1. A strap wrench, comprising a block having an inclined slot therein and a flat surface, ears projecting from said block, a head pivoted to the ears, a strap passing through and fixed in the slot, and a flat surface on the head adapted to cooperate with the flat surface of the block to tightly grip the strap. 75

2. A strap wrench, comprising a block having a slot therein and a rounded gripping surface projecting beyond the sides of the block, said block having an inclined flat surface on the side opposite the rounded gripping surface, a strap passing through the slot and over the inclined surface, a head pivotally connected to the block, said head having a flat surface substantially parallel to and cooperating with the inclined flat surface to grip the strap, and a handle 80 attached to the head. 85

3. A strap wrench, comprising a block having a strap attached to one side thereof, said block having an inclined flat surface over which the strap passes, and a head pivotally connected to the block, said head having a flat surface adapted to cooperate with the inclined flat surface to tightly grip the strap. 95

4. A strap wrench, comprising a block 100 having a strap attached thereto, said block having a gripping surface and an opposite flat surface over which the strap passes, and a head pivotally connected to the block, said head having a flat surface cooperating with 105 said opposite flat surface to tightly grip the strap.

This specification signed this 23rd day of March, 1932.

FREDERICK E. DERINGER. 110
This specification signed this 25th day of March, 1932.
